UNITED STATES PATENT OFFICE.

JOHN T. MCROY, OF CHICAGO, ILLINOIS.

DESIGN FOR A CONDUIT-SECTION.

SPECIFICATION forming part of Design No. 34,968, dated August 20, 1901.

Application filed December 27, 1900. Serial No. 41,291. Term of patent 14 years.

To all whom it may concern:

Be it known that I, JOHN T. MCROY, a citizen of the United States, residing at Chicago, in the county of Cook and State of Illinois, have invented and produced a new and original Design for Conduit-Sections, of which the following is a specification, reference being had to the drawing forming a part thereof.

Said drawing represents a view in perspective of a conduit-section embodying the design.

As shown in the drawing the leading feature of the design consists in providing each of the four walls or sides of a conduit-block with a V-shaped groove arranged in the planes of the partitions of the block and in providing the end of the block with a central socket or recess.

The conduit-block A is rectangular in shape and is provided with two partitions D, that are placed at right angles to each other, so as to divide the conduit-block into four longitudinal ducts B. The end of the block is

provided, as shown in the drawing, with a central socket or recess formed in the junction of the partitions. Each of the sides of the duct is provided on its exterior with a longitudinal V-shaped groove that extends the entire length of the block. Said grooves are arranged in the planes of the partitions and coincide therewith, so that the thickness of the wall between the groove and each duct shall be approximately the same as the thickness of the other portions of the exterior wall of the duct. 35

I claim as my invention—

The design for a conduit-section, substantially as shown and described.

In testimony whereof I sign this application, in the presence of two witnesses, this 21st 40 day of December, 1900.

JOHN T. MCROY.
